UNITED STATES PATENT OFFICE.

RICHARD DUDLEY AND BENJAMIN HERSHY, OF ERIE, PENNSYLVANIA,
ASSIGNORS OF ONE-THIRD OF THEIR RIGHT TO FRANK M. CRANE, OF
SAME PLACE.

CLOTHES-WRINGER.

SPECIFICATION forming part of Letters Patent No. 229,107, dated June 22, 1880.

Application filed May 7, 1880. (No model.)

To all whom it may concern:

Be it known that we, RICHARD DUDLEY and BENJAMIN HERSHY, citizens of the United States, residing at Erie, in the county of Erie and State of Pennsylvania, have invented new and useful Improvements in Clothes-Wringers, of which the following is a specification.

This invention has for its object to produce a wringing and washing machine which will be simple and cheap in construction, and in which the spring-pressure upon the clothes will be automatically regulated by the thickness of the body of the clothes passing between the rollers, as more fully hereinafter specified.

The invention consists, first, in the combination, with the frame of a clothes-wringer and the upper wringer-roll thereof, of a torsional spring extending longitudinally along the rear of the wringer-frame, and having its ends bent downward to the front of the frame, and provided with eyes or bearings carrying the ends of the upper wringer-roll; second, in the combination, with the frame of a clothes-wringer having a top cross-piece connecting the side frames, and with the lower and upper wringer-rolls, of a torsional spring extending longitudinally along the frame, and having its ends bent substantially at right angles, and provided with eyes or bearings carrying one of the wringer-rolls, and mechanism for regulating the tension of the torsion-spring; third, in a torsional spring provided with downward and forward projecting bent ends and a vertically-projecting loop or arm, in combination with the wringer-roll, connected by eyes or bearings with the bent ends of the torsion-spring, and an adjusting-screw passing through the wringer-frame, and provided with a head against which the loop or arm bears, for regulating the tension of the torsion-spring; fourth, in the combination, with a wringer, of two swiveled clutches adapted to be set over the edge of a tub, with means by which they can be operated to bind upon the edge of the tub, as more fully hereinafter set forth.

In the drawings, Figure 1 is a perspective view of our improved wringer and washer.

Fig. 2 is a longitudinal vertical section taken on the plane of the axes of the rollers. Fig. 3 is a transverse vertical section through the base-board, back board, and lower roller, showing the drip-plate. Fig. 4 is a detached sectional view, showing a modified form of the back board. Fig. 5 is a detached view, showing a modification of the bearings at ends of the spring; and Fig. 6 is a section of the cross-piece of the wringer-frame on the line *x* *x* of Fig. 2.

The letter *A* indicates the base of the wringer, supporting at its opposite ends the vertical standards *B*, connected at their tops by the cross-piece *C*.

The letter *D* indicates the lower roller, the shaft of which is journaled in fixed bearings *E*, formed in the lower part of the vertical standards *F*.

The letter *G* indicates the upper roller, which is journaled in eyes or bearings *H* at the ends of the spring *I*, by which a spring-pressure is given to said upper roller, so as to permit it to yield as the clothes are passed between the rollers, in the manner more fully hereinafter specified. The said spring *I* is pivoted to the rear or front of the cross-piece *C*, and its ends are bent downward and to the front of the machine, so as to hold the upper roller directly above the lower one and permit the said upper roller to be elevated in the arc of a circle upon a radius formed by the bent ends of the spring when the clothes are passed between the rollers. The spring *I* is bent into the form of a loop or arm, *K*, at its center or other portion or portions.

The letter *L* indicates an adjusting-screw passing through the loop *K* and provided with a head against which said loop bears. (See Fig. 6.) This screw also passes through an aperture in the cross-piece *C*, whereby the tension of the spring may be regulated and controlled to produce the proper pressure upon the clothes.

On account of cheapness and simplicity the arm *K* is preferably formed by bending the spring, as just above mentioned; but it is evident that the arm could be otherwise formed without departing from our invention, such

as making the arm and journal-bearing in one piece.

The bearings at the end of the spring, where extreme simplicity and cheapness are an object, consist simply of eyes or loops formed at the ends of the spring-arm, as indicated at Fig. 5 of the drawings; but they are preferably formed of boxes carrying friction balls or rollers to lessen friction. The lower roller may also be journaled in ordinary boxes, or in boxes provided with friction balls or rollers, as may be desired or found convenient.

The letter M indicates a vertical plate, which we term a "drip-plate," extending longitudinally along the front of the back board N of the wringer. The said plate is provided with a longitudinal bead, O, at its upper edge, which is adapted to set between the upper edge of the back board and the periphery of the lower roller, and serves to direct the water back into the wash-tub or vessel to which the wringer is attached.

The letter P indicates two clutches swiveled to vertical rods or pins R, depending from the base of the wringer near each end. The said clutches are provided with slots S, by means of which they can set upon the edge of the tub or other vessel.

The letter T indicates a rod provided with a head at one end and a screw-thread at the other, and passing loosely through apertures U in the respective clutches, the screw-threaded end of the rod having mounted thereon a handle, V, by means of which the clutches may be drawn toward each other and cause the opposite sides of the slots to bind against the tub and hold the wringer or washer firmly thereon.

The operation of our invention will be readily understood in connection with the above description. The clothes are passed between the rollers in the usual manner, the upper roller yielding for the purpose, and, as it moves in the arc of a circle on the ends of the spring, it will be perceived that as it becomes elevated and the tension of the spring increased the leverage of the ends of the spring is correspondingly increased, thus automatically regulating the pressure upon the clothes, so

as to preserve a uniform pressure, irrespective of the thickness of the body of the clothes.

It will be manifest that the arrangement of the spring can be changed so as to act on the lower roller instead of the upper one, and therefore we do not confine ourselves to the precise arrangement shown.

What we claim is—

1. The combination, with the frame of a clothes-wringer and the upper wringer-roll thereof, of the torsional spring I, extending longitudinally along the rear of the wringer-frame, and having its ends bent downward to the front of the frame, and provided with eyes or bearings carrying the ends of the upper wringer-roll, substantially as described.

2. The combination, with the wringer-frame having the cross-piece C, and with the lower and upper wringer-rolls, D G, of the torsional spring I, extending longitudinally along the frame, and having its ends bent at right angles, and provided with eyes carrying the wringer-roll G, and mechanism, substantially as described, for regulating the tension of the torsion-spring.

3. The torsional spring I, formed with the downward and forward projecting bent ends, and the vertically-projecting loop or arm K, in combination with the upper roll, connected by eyes with the bent ends of the torsion-spring, and the adjusting-screw L, passing through the wringer-frame and provided with a head, against which the loop or arm bears, substantially as and for the purpose described.

4. In combination with a clothes-wringer, the swiveled clutches, screw-connecting rod, and screw-nut, whereby said clutches can be drawn toward each other and caused to bind upon the edge of a tub or other vessel, substantially as specified.

In testimony whereof we have hereunto set our hands in the presence of two subscribing witnesses.

RICHARD DUDLEY.
BENJAMIN HERSHLEY.
